United States Patent Office

Des. 181,444
Patented Nov. 12, 1957

181,444

WRIST WATCH BRACELET

John F. Sand, Convent Station, and William Hoehn, Springfield, N. J., assignors to The Gemex Corporation, New York, N. Y., a corporation of New Jersey

Application March 22, 1957, Serial No. 45,405

Term of patent 14 years

(Cl. D45—4)

Fig. 1.

Fig. 2.

Fig. 1 is a developed plan view of a wrist watch bracelet embodying our new design; and

Fig. 2 is a side elevational view thereof.

The dominant features of the design reside in the portion shown in full lines.

We claim:

The ornamental design for a wrist watch bracelet, as shown and described.
